UNITED STATES PATENT OFFICE.

ANTONIN PLAČEK, OF CLEVELAND, OHIO, ASSIGNOR TO THE VLCHEK TOOL CO., OF CLEVELAND, OHIO, A CORPORATION OF OHIO.

WORK-HOLDING DEVICE.

1,324,269.

Specification of Letters Patent.

Patented Dec. 9, 1919.

Application filed May 16, 1918. Serial No. 234,908.

To all whom it may concern:

Be it known that I, ANTONIN PLAČEK, a subject of Austria, residing at Cleveland, in the county of Cuyahoga and State of Ohio, have invented certain new and useful Improvements in Work-Holding Devices, of which the following is a specification.

This invention relates to work holding devices, and more particularly to a device for attachment to the table of a drill-press for holding work to be scraped or reamed.

The main object of the invention is to provide a device which will hold, a piece of work such as tubing having a plurality of flat sides, in such a manner that a rotating tool will scrape off the burs produced upon the inner corners of the ends thereof when sawing the tube in lengths.

Another object of the invention is to provide a device of said character, in which adjustment may be made so that the rotating tool will take off the burs at the corners just flush with the sides of the tubing and thus leave perfectly square end corners.

A further object of the invention is to provide such a device having simple means for quickly clamping the work in place and releasing it.

With the above and other objects in view as will be understood, the invention will be hereinafter fully described in connection with the accompanying drawings, and the novel features thereof will be distinctly pointed out in the appended claims.

Like characters of reference are used in the drawings to indicate corresponding parts.

Figure 1 is a front elevation of a device constructed in accordance with my invention.

Fig. 2 is a side elevation of the same,

Fig. 3 is a plan view of the clamping means,

Fig. 4 is a sectional view illustrating the spring adjusting screw,

Fig. 5 is an end view of a several sided tube,

Fig. 6 is a perspective view of a scraping or reaming tool used in connection with the work holding device,

Fig. 7 illustrates the device holding a piece of tubing, which is being acted upon by the tool and thereby causing the tilting motion, and

Fig. 8 is a plan view illustrating the tub-

ing held by the clamping means and the tool acting thereupon.

In the drawings, 1 represents a base to the opposite edges of which are fixed a pair of legs 2 and 3 formed integrally with a cross-bar 4 of a rectangular yoke.

The legs 2 and 3 are provided with vertical slots 5 near the cross-bar 4 for receiving a pair of trunnions 6 and 7, which are fixed into the opposite edges of a rectangular plate 8. A pair of upwardly extending sides 9 and 10 are fixed to the other opposite edges of the plate 8, and these sides carry quick acting clamping means for holding the work. Said clamping means consists of a pair of complementary jaws 11 and 12, having horizontally projecting guide pins 13, which are slidably mounted in openings of the sides 9 and 10. The jaws 11 and 12 are actuated by means of a right and left hand threaded screw 14, which operates in rearwardly extending ears 15 and 16 of said jaws, and is rotatably mounted in openings of flanges 17 and 18 forming a part of the sides 9 and 10. A separating collar 19 is fixed to the center of the screw 14, and the screw is provided with a handle 20 for rotating the same.

For resiliently supporting the plate 8, a suitable coiled spring 21 is arranged between the same and the base 1, and it is thus supported so that it may rock upon its trunnions 6 and 7, or may tilt, in which latter case the trunnions slide in opposite directions in the slots 5. The coiled spring 21 is held in a central position upon the base by means of pins 22. For changing the tension of the coiled spring 21, in order that it may be adjusted so as to exert the proper action upon the plate 8 for resiliently supporting the work in the best manner, an adjusting screw 23 is employed. Said adjusting screw is threaded in the cross-bar 4, and is provided with a suitable pivot point 24 for engaging the plate 8, which is provided with a central recess for receiving the same. A lock-nut 25 retains the adjusting screw 23 in its set position.

In practice, the base 1 is fastened in any suitable manner to the table of an ordinary drill-press, and a suitable tool such as 26 is fixed in the rotating chuck of the machine.

The tool 26 is made with an off-center triangular tapering point 27 having sharp scraping or cutting edges 28. When sawing

off short lengths of tubing from a plural sided tube such as shown in cross section at 29, burs illustrated at 30, are formed upon the inner corners of the ends thereof. It 5 is a slow and tedious process to remove the burs by filing off the same by hand, but by clamping the tubing 29 between the jaws 11 and 12, and feeding the rotating off-center tool 26 of the drill-press in the usual 10 manner into the end of the tubing, the burs are removed quickly. This is accomplished by the sharp edges 28 of the rotating tool 26 scraping along the inner edges of the tubing 29, due to the cutting end of the tool 15 being off-center and the sharp edges thereof striking the inner corners 31 of the tubing, which is rocked and tilted thus producing a wabbling motion. It is important to have the coiled spring 21 exert the proper tension 20 against the plate 8; to meet the different conditions, and the adjusting screw 23 may be set to force the plate downwardly upon the coiled spring or permit the plate to move upwardly, thereby varying the tension of the 25 coiled spring.

It will be understood that slight changes may be made in the construction of the holding device, and also in the scraping tool without departing from the scope of the 30 appended claims.

Having fully described my invention, what I claim is:

1. In a work holding device, the combination of a base, a pair of sides resiliently supported by the base to permit tilting thereof, and means carried by the sides for holding work, substantially as described.

2. In a work holding device, the combination of a base, a pair of sides resiliently supported from the base to permit tilting thereof, means for changing the resiliency between the sides and the base, and means carried by the sides for holding work, substantially as described.

3. In a work holding device, the combination of a base, a pair of sides resiliently supported by the base to permit a rocking movement thereof and a tilting movement at a right angle to the rocking movement, and means carried by the sides for holding work, substantially as described.

4. In a work holding device, the combi-

nation of a base, a pair of legs fixed to the base, a pair of sides arranged at a right angle to the legs, means for resiliently supporting the sides from the legs, and means carried by the sides for holding work, substantially as described.

5. In a work holding device, the combination of a base, a pair of legs fixed to the base, the legs being provided with slots, a plate, trunnions supporting the plate in the slots, resilient means supporting the plate, a pair of sides fixed to the plate, and means carried by the sides for holding work, substantially as described.

6. In a work holding device, the combination of a base, a pair of legs fixed to the base, the legs being provided with slots, a plate, trunnions supporting the plate in the slots, a spring arranged between the plate and the base, means for changing the tension of the spring, a pair of sides extending from the plate, and means carried by the sides for holding work, substantially as described.

7. In a work holding device, the combination of a base, a pair of sides resiliently supported by the base, a pair of jaws slidably mounted in the sides, and a right and left hand screw threaded in the jaws for operating the same, substantially as described.

8. In a work holding device, the combination of a base, a pair of legs fixed to the base, the legs being connected by a cross-bar, the legs being provided with slots, a plate, trunnions supporting the plate in the slots, a spring supporting the plate from the base, an adjusting screw threaded in the cross-bar and bearing upon the plate for changing the tension of the spring, a pair of sides fixed to the plate at right angles to the trunnions, and clamping means carried by the sides for holding the work, substantially as described.

9. In a device of the class described, the combination of means for resiliently holding work so that it may tip, and a rotating tool having an off-center scraping end for acting upon the work, substantially as described.

In testimony whereof I affix my signature.

ANTONIN PLAČEK.
